ILLUMINABLE ADVERTISING SIGN

Joseph A. Winger, Greenwich, Conn., assignor to The Texas Company, New York, N. Y., a corporation of Delaware

Application June 19, 1956, Serial No. 41,965

Term of patent 14 years

(Cl. D1—12)

Fig. 1 is a perspective view of an illuminable sign showing my new design, the shaded portion indicating contrasting color;

Fig. 2 is a side elevational view thereof; and

Fig. 3 is a top plan view of Fig. 1.

The rear of the sign is substantially like the side shown.

I claim:

The ornamental design for an illuminable advertising sign, as shown.
